UNITED STATES PATENT OFFICE.

THOMAS L. DAVENPORT, OF EVERETT, WASHINGTON.

VACUUM-JET.

1,180,017.

Specification of Letters Patent. Patented Apr. 18, 1916.

Application filed March 31, 1915. Serial No. 18,312.

To all whom it may concern:

Be it known that I, THOMAS L. DAVENPORT, citizen of the United States, residing at Everett, in the county of Snohomish and State of Washington, have invented a certain new and useful Improvement in Vacuum-Jets, of which the following is a specification.

My invention relates to improvements in vacuum-jet pumping systems and the object of my improvement is to provide a vacuum-jet pumping system which shall embody a plurality of vacuum-jet pumps and conduits, together with controlling valves that are adapted to operate conjointly and automatically to control and regulate the flow of fluid in such conduits, whereby the supply of fluid under pressure for operating such system shall at all times be proportionate to the effective work thereof, and a further object of my improvement is to provide a vacuum-jet pumping system that shall be adapted for use in a building in removing dirt and dust from the rooms of such building to a desired place of disposal and that shall be further adapted to operate to create a greater power of suction than has been possible in vacuum-jet pumping systems heretofore employed whereby conduits of a given cross-sectional area shall have greater capacity. I accomplish these objects by devices illustrated in the accompanying drawings wherein—

Figure 1 is a view in vertical mid-section of a structure embodying the operative parts of my invention; Fig. 2 is a view of the same in horizontal cross-section on broken line x, x , of Fig. 1; Fig. 3 is a view of the same in horizontal cross-section on broken line y, y of Fig. 1; and Fig. 4 is a view in vertical mid-section of certain parts of a modified form of my invention some other parts being shown by a view in side elevation.

Referring to the drawings, throughout which like reference numerals indicate like parts, 5 is a conduit pipe, which may be extended to a convenient place of deposit of matter forced to flow therethrough, to the upper screw-threaded end of which conduit pipe 5 is connected the internally screw-threaded lower end of a cylindrically formed vacuum-jet 6 to whose upper internally screw-threaded end is connected the externally screw-threaded lower end of another vacuum-jet 7 whose upper internally screw-

threaded end is connected with the lower externally screw-threaded end of a vacuum-jet comprising a lower part 8 and an upper part 9, the upper internally screw-threaded end of which part 8 is connected with the lower externally screw-threaded end of said part 9.

Projecting from the periphery of the part 9 of the uppermost vacuum-jet is a boss 10 and extending through said boss 10 and the wall of the part 9 is a screw-threaded hole into which is screwed one end of a supply pipe 11 through which steam, compressed air or liquid under pressure may find its way into the part 9 of said uppermost vacuum-jet where it is received within an annular space 21 which extends around the wall of a tube 12 that is concentrically disposed to project downwardly from the top wall of the part 9 of which it is an integral part and which tube 12 has its bottom end provided with an externally beveled portion which terminates with its beveled surface disposed near to and concentrically with a corresponding internally beveled surface of the throat of the main passageway 13 that extends downwardly through the part 8 of the uppermost vacuum-jet, the walls of which passageway 13 form a tube 14 shaped like the frustum of a cone, and the lower large end of such tube 14 is likewise provided with an externally beveled portion which terminates with its beveled surface disposed near to and concentrically with the internally beveled throat of the main passageway 15 that extends downwardly through the vacuum-jet 7, the walls of which passageway 15 form a similar but larger tapered tube 16 whose lower larger end is likewise provided with an externally beveled portion which terminates with its beveled surface disposed near to and concentrically with the internally beveled throat of the passageway 17 formed by the larger tapered walls of the vacuum-jet 6 whose lower end connects with the conduit pipe 5 as illustrated in Fig. 1.

The tubes 14 and 16 are supported in their concentric positions within their respective vacuum-jets by means of integral wheel-like spokes 18, as more clearly indicated by Fig. 3, whereby they are surrounded by annular spaces 19 and 20, respectively, which annular spaces 19 and 20 communicate with the annular space 21 thus to permit fluid under pressure to flow from the

pipe 11 to supply such fluid to the annular spaces 21, 19 and 20 from which annular spaces such fluid may gain access into the main passageways 13, 15 and 17, through the space between the beveled surfaces at the adjacent ends of the respective ones of the three vacuum-jets, to be directed downwardly with great velocity into the conduit pipe 5 thus tending to create a vacuum within the passageway that extends through the tube 12 of the upper part 9 of the uppermost vacuum-jet.

An important feature of my invention consists in constructing the several vacuum-jets so that when they are joined together then the passageways 13, 15 and 17 shall constitute a continuous passageway that increases at a constant rate in its diameter between the inlet end of the uppermost vacuum-jet and the outlet end of the lowermost one of said vacuum-jets, as shown in Fig. 1, thereby preventing retarding eddy currents of fluid that otherwise would occur, as for instance, if the walls of such passageway be diverged at an inconstant angle.

The passageway extending upwardly through the tube 12 communicates with the interior chamber 30 of a check-valve 22 whose externally screw-threaded lower end portion is screwed into the top wall of the upper part 9 of the uppermost vacuum-jet and whose upper end is provided with a screw-threaded hole within which is screwed an annular bushing 23 whose lower end portion projects downwardly within the chamber 30 of the check-valve 22 where it is formed to engage with the beveled surface of a valve member 24 whereby the passageway through said bushing 23 may be maintained normally closed in response to the force of a helical spring 25 that is disposed to surround the valve-stem 26 which valve-stem 26 is an integral part of the valve 24 and which is slidably disposed within a concentrically disposed socket 27 that is supported in its concentric position by webs 28, as more clearly shown in Fig. 2.

Into the upper end of the bushing 23 is screwed a conduit pipe 29 which may be extended to connect with one or more conduit pipes through which air is to be sucked. To the outer end of the pipe 11 is connected the outlet end 31 of a globe-valve 32 whose inlet end 33 is connected to a supply pipe 34 leading to a source of fluid under pressure, and interposed within said supply pipe 34 is a strainer 35 comprising a disk of perforated sheet metal or wire netting clamped between two flanged members 36 and 37 of concavo-convex form, as shown in Fig. 1, which strainer 35 may serve to prevent obstructive matter from being carried into the globe-valve 32 and its associated vacuum-jets.

65 The globe-valve 32 embodies a beveled

valve member 38 which is mounted on a spindle 39 that is disposed to extend upwardly from the globe-valve 32 into a bored cylinder 40 whose bottom end is screwed into the top side of the globe-valve 32 and whose top end is open, and mounted on said spindle 39 is a piston 41 which is thus adapted to fit and be movable within the boring of said cylinder 40. A helical compression spring 42 is disposed to surround said spindle 39 to extend between said piston 41 and the inner surface of the bottom of said cylinder 40 whereby said piston 41 and the spindle 39 may be normally maintained in a position so that the valve member 38 shall be raised from its seat 43 to open the passageway through the globe-valve 32 in an obvious manner. Extending between the lower portion of the cylinder 40 and the conduit pipe 29 is a pipe 44 which provides a passageway between the interior of the cylinder 40 and the interior of the pipe 9 through which air may flow, and connected with the upper portion of said pipe 44 is a vacuum-gage 45 which may indicate the degree of minus pressure within the conduit pipe 29 and within the cylinder 40.

The operation of my invention as embodied in the structure illustrated by Figs. 1, 2 and 3 may be described as follows: The conduit pipe 29 being associated with a system of conduit pipes, through which air is to be sucked to carry with it the dirt and dust of rooms of a building within which such system is installed to deliver such dirt and dust through the delivery pipe 5 to a convenient place of deposit of such matter, and the pipe 34 being extended to connect with a valve-controlled outlet of a supply of steam or compressed air, then normally the valve member 24 and the valve member 38 are in their respective positions, as shown in Fig. 1, whereby the passageway between the pipe 29 and the chamber 30 is closed, while the passageway through the globe-valve 32 is open; then if steam or compressed air is admitted into the pipe 34 from the valve controlled outlet of a source of supply, not shown, such compressed air or steam will pass through the strainer 35, thence through the globe-valve 32 into the annular spaces 21, 19 and 20 of the several vacuum-jets, thence between the beveled adjacent surfaces at the throats of the several vacuum-jets into the passageways 13, 15 and 17 thereof, thence to flow downwardly through the pipe 5 whereupon there will be a tendency to create a vacuum in the chamber 30 which will cause the valve member 24 to move downwardly against the force of the helical spring 25 to open the passageway between the pipe 29 and said chamber 30 thus to tend to create a vacuum in said pipe 29 and in the cylinder 40. If the work to be done by the system of conduit pipes

connected with the pipe 29 is slight then the tendency to form a vacuum in such system and in the cylinder 40 will be greater with the result that atmospheric pressure on the top of the piston 41 will move such piston 41 downwardly to decrease the flow of steam or compressed air into the vacuum-jets, and if the intakes of said system of conduit pipes are all closed then such atmospheric pressure will cause the piston 41 to wholly close the globe-valve 32, but if the maximum amount of work is being effected by said system by reason of all of its intakes being open then the spring 42 will be strong enough to raise the valve member 38 to its highest point against the atmospheric pressure on the piston 41; thus by the coaction of the valve members 24 and 38 the degree of minus pressure in the system of conduit pipes and in the cylinder 40 will be automatically regulated to be substantially constant irrespective of the amount of work being effected by the system of conduit pipes, and the rate of flow of compressed air or steam into the several vacuum-jets through the globe-valve 32 will be always proportionate to the amount of work being effected through said system of conduit pipes. The vacuum-gage 45 may serve to determine the adjustment of the helical springs 25 and 42 which may be supplied with some well known form of devices, not shown, whereby their adjustment may be altered if desired.

In Fig. 4 I have shown a modified form of structure which differs from the structure of Figs. 1, 2 and 3 only in respect to the valve controlling mechanism. In Fig. 4 the conduit pipe 46, the check-valve 47, the valve members 48 and 49 correspond respectively to the conduit pipe 29, check-valve 22 and valve members 24 and 38 of Fig. 1, and also the valve-stem 26 and the valve-spindle 39 of Fig. 1, correspond respectively with the valve-stem 50 and the spindle 51 of Fig. 4, and in Fig. 4 the valve-stem 50 and the spindle 51 are operatively connected together by a lever 52 pivotally secured to a bracket 53 attached to the outer side of the check-valve 47, one end of said lever 52 being articulated to a pin 54 disposed to extend through the valve-stem 50 while the other end of said lever 52 is yieldingly articulated with the upwardly extended portion of the valve spindle 51 which projects upwardly through a piston 55 which corresponds to the piston 41 of Fig. 1. Thus by means of such lever 52 the valve members 48 and 49 normally operate to move in unison, and in an obvious manner when the suction through the pipe 46 tends to vary from a desired normal degree

by reason of variation in the work being done in the system of conduit pipes with which the pipe 46 is connected, then the valve members 48 and 49 will move in unison to change the rate of flow of fluid through the respective passageways which they control.

Manifestly changes may be made in the number of vacuum-jets and in the forms, dimensions and arrangement of parts embodied in my invention without departing from the spirit thereof.

What I claim is:

1. In a vacuum-jet pumping system of the class described, the combination with a plurality of vacuum-jets, the main passageway through each of which is of the form of the frustum of a cone and of a different mean diameter, all of said vacuum-jets being connected together in series so that their combined passageways may form a continuous passageway that shall increase in its diameter at a constant rate from the inlet end to the outlet end of said series, of a delivery conduit connected to the outlet end of said series of vacuum-jets, a check-valve whose outlet end is connected to the inlet end of said series, an intake conduit connected to the inlet end of said check-valve, a fluid supply pipe disposed to adapt it to conduct fluid under pressure into the several throats of said vacuum-jets, and automatic means associated with said supply pipe and with said intake conduit whereby the flow of fluid through said supply pipe shall be varied in response to variations in the minus pressure of fluid within said intake conduit.

2. A vacuum jet pumping system, which embodies a vacuum jet; a check-valve whose outlet end is connected with the inlet end of said vacuum jet; a suction conduit connected with the inlet end of said check-valve; a pipe connected with said vacuum jet through which pipe fluid under pressure may be conducted into the throat of said vacuum jet; a valve connected with said pipe to control the passage-way therethrough; and a pivotally supported lever disposed to extend between the valve-stem of said valve and the valve-stem of said check-valve in an articulated relation thereto whereby said valve and said check-valve shall operate synchronously and independently.

In witness whereof, I, hereunto subscribe my name this twenty sixth day of March A. D., 1915.

THOMAS L. DAVENPORT.
